(57) **CLAIM**

The ornamental design for a toy torpedo, as shown and described.

DESCRIPTION

The patent or application file contains at least one drawing executed in color. Copies of this patent or patent application publication with color drawing(s) will be provided by the Office upon request and payment of the necessary fee.

FIG. 1 is an upper right side perspective view of a first embodiment of the toy torpedo.

FIG. 2 is a lower left side perspective view of the first embodiment of the toy torpedo.

FIG. 3 is a front view of the first embodiment of the toy torpedo.

FIG. 4 is a right end view of the first embodiment of the toy torpedo.

FIG. 5 is a rear view of the first embodiment of the toy torpedo.

FIG. 6 is a left end view of the first embodiment of the toy torpedo.

FIG. 7 is a top view of the first embodiment of the toy torpedo.

FIG. 8 is a bottom view of the first embodiment of the toy torpedo.

FIG. 9 is an upper right side perspective view of the second embodiment of the toy torpedo.

FIG. 10 is a lower left side perspective view of the second embodiment of the toy torpedo.

FIG. 11 is a front view of the second embodiment of the toy torpedo.

FIG. 12 is a right end view of the second embodiment of the toy torpedo.

FIG. 13 is a rear view of the second embodiment of the toy torpedo.

FIG. 14 is a left end view of the second embodiment of the toy torpedo.

FIG. 15 is a top view of the second embodiment of the toy torpedo.

(Continued)

FIG. 16 is a bottom view of the second embodiment of the toy torpedo.
FIG. 17 is an upper right side perspective view of the third embodiment of the toy torpedo.
FIG. 18 is a lower left side perspective view of the third embodiment of the toy torpedo.
FIG. 19 is a front view of the third embodiment of the toy torpedo.
FIG. 20 is a right end view of the third embodiment of the toy torpedo.
FIG. 21 is a rear view of the third embodiment of the toy torpedo.
FIG. 22 is a left end view of the third embodiment of the toy torpedo.
FIG. 23 is a top view of the third embodiment of the toy torpedo; and,
FIG. 24 is a bottom view of the third embodiment of the toy torpedo.
